UNITED STATES PATENT OFFICE.

HEINRICH WILHELM FRIEDRICH JAEGER, OF CLEVELAND, OHIO.

ADJUSTABLE GRAIN-DOOR.

1,057,965.

Specification of Letters Patent.

Patented Apr. 1, 1913.

Application filed April 18, 1912. Serial No. 691,696.

To all whom it may concern:

Be it known that I, HEINRICH WILHELM FRIEDRICH JAEGER, a citizen of the United States, and a resident of Cleveland, in the county of Cuyahoga and State of Ohio, have invented a new and Improved Adjustable Grain-Door, of which the following is a full, clear, and exact description.

This invention relates to improvements in doors for cars designed to carry grain, and has for an object to provide an improved structure which may be adjusted or expanded so as to permit grain of different weights to be shipped in the same car without changing the door and without reducing the amount of grain which may be safely shipped in any particular car.

Another object of the invention is to provide a grain door formed in a plurality of parts and arranged with apertures on one side co-acting with a locking pin designed to be projected through the respective apertures according to the height of the adjustable portion of the door so as to hold the same in any adjusted position.

In carrying out the objects of the invention, a door is provided which is hinged in position in the car so as to swing or to be pivoted to one side when it is desired to open the door.

One construction of a grain door of a somewhat similar nature to the present invention is disclosed in my Patent No. 554,932, issued February 18, 1896. In the present invention the same shows an improvement over this former patent by the particular arrangement and construction of the door and means for holding the same in various positions. The door is provided with a lower portion which is pivotally mounted to the car to which it is attached, and which is associated with a movable portion designed to be raised upward to close to a greater or less extent the entire doorway. A pin is arranged in one side of the door casing which is adapted to be projected through various apertures provided in the adjustable door at various times so as to hold the door at varying heights. This is of advantage as the different grains have different weights. When a heavy grain is being shipped, as for instance wheat, the adjustable portion of the door is left in its lowermost position as the car will not support more than approximately half of a load, while lighter grain, as for instance

oats, may be placed in the car until the car is two-thirds full or possibly more. In order to prevent the oats from being discharged out the door, the adjustable portion of the door is raised to a point preferably slightly above the upper level of the grain.

A practical embodiment of the invention is represented in the accompanying drawings forming a part of this specification, in which similar characters of reference indicate corresponding parts in all the views.

Figure 1 is a fragmentary side view of a car showing the door opening and an embodiment of the invention applied thereto; Fig. 2 is a section through Fig. 1 on the line 2—2; Fig. 3 is a view similar to Fig. 1, except that the same is looking from the interior of the car outwardly; and Fig. 4 is a section through Fig. 3 on the line 4—4.

Referring to the accompanying drawings by numerals, 1 indicates a car body of any description, provided with the usual door opening 2 in which is arranged a grain door 3. Arranged adjacent the door opening 2 is the ordinary outside sliding door 4 which not only covers the door opening but also the grain door 3 when in a closed position. The door 4 may be of any desired or usual construction. The door 4 carries a projecting hook 5, a locking staple 6, and a bolt or latch 7. When the door 4 is closed the hasp 8 is moved over until the projection 9 fits over the projecting hook 5 and the staple 6 is caused to project into the slot 10, the hook 7 being previously moved out of engagement with the staple.

The hasp 8 is provided with a pressed out cup-shaped portion 11 which fits over the end of a pin 12 and also over the operating ring 13 connected therewith and protects the same against being tampered with when the hasp 8 is closed. After the hasp 8 has been closed the hook 7 is again caused to engage the staple 6 so as to hold the door temporarily closed, or a lock of any kind, as for instance an ordinary padlock is brought into engagement with the staple 6 when it is desired to positively prevent the opening of the door. The door 4 is an outside protecting door, while the door 3 is designed to sustain the weight of the grain in the car, and to prevent any of the same from passing out of the doorway. The door 3 is formed with an outer door portion 14 and an adjustable door portion 15. The outer door portion 14

is provided with an aperture near the top for accommodating the pin 12, and an aperture near the bottom for accommodating a pivotal pin 16. Preferably the lower edge 5 of the inner adjustable door portion 15 is held normally in line with the upper edge of the pin 16 when in the lower position. The adjustable door portion 15 is provided with a plurality of apertures 17 into which 10 the pin 12 is designed to be thrust or projected whenever it is desired to hold the inner door 15 in any adjusted position. The pin 12 is designed to reciprocate in a suitable aperture in the side of the car and is 15 formed with a stop 18 designed to move in a housing 19 containing a spring 20 which normally holds the pin in an inner position, as shown in Fig. 4. The pin may be moved from this position by an outward movement 20 of the ring 13 so as to permit a vertical adjustment of the inner door portion 15. If desired, the inner door portion 15 may be moved upward until the handholds 21 and 22 are in position to have the hooks 23 and 25 24 positioned therein for holding in an elevated position the door portion. This is desirable where hay or other light material is to be shipped. By the construction and arrangement of the pin 12 and associated parts 30 with the aperture 17, the inner door portion 15 may be easily adjusted at any height, while by the provision of the pin or bolt 16 the car door 3 may be swung to one side, as shown in dotted lines in Fig. 3, for exposing 35 the entire door opening.

Having thus described my invention I claim as new and desire to secure by Letters Patent:—

1. In a grain door of the class described, 40 the combination with a door frame, of a pivotally mounted door, a stationary pin for pivotally connecting said pivotally mounted door with said frame, a reciprocating spring-pressed pin mounted in said frame, an aperture 45 formed in said pivotally mounted door for accommodating said pin whereby the pivotally mounted door is locked against pivotal movement when the reciprocating

pin is projecting into said aperture, a vertically adjustable section associated with 50 said pivotally mounted door, said vertically adjustable section being formed with a row of apertures adapted to accommodate said reciprocating spring-pressed pin at different places whereby the vertically adjustable section is held in its adjusted position and said pivotally mounted door is held against pivotal movement.

2. In a grain door of the class described, the combination with a stationary door frame, of a door pivotally connected therewith, said pivotal connection being at one of the lower corners so that the door may be swung pivotally in a plane parallel with the frame, a pin adapted to extend through said frame and into said door, and a vertically adjustable section formed with a plurality of apertures associated with said door, said reciprocating pin being adapted to fit into any of said apertures for holding said section in various adjusted positions and simultaneously locking said door against pivotal movement.

3. In a grain door of the class described, a door structure formed with an extension 75 member, said door structure being formed with an aperture near the upper edge and said extension member being formed with a row of apertures near one edge designed to at various times register with the aperture 80 in the door structure, a journal member passing through one part of said door structure and extending in such a direction as to cause the door structure to move pivotally only in a vertical plane, a locking pin adapted to 85 project through any of the apertures in said extension and through the aperture in said door structure, and means for normally holding said pin in said aperture.

In testimony whereof I have signed my 90 name to this specification in the presence of two subscribing witnesses.

HEINRICH WILHELM FRIEDRICH JAEGER.
